GEORGE E. A. HALLETT, OF DAYTON, OHIO, ASSIGNOR TO GENERAL MOTORS RESEARCH CORPORATION, OF DAYTON, OHIO, A CORPORATION OF DELAWARE.

VALVE-OPERATING MECHANISM.

Application filed November 24, 1924. Serial No. 751,778.

This invention relates to improvements in valve mechanism for internal-combustion engines and more particularly to such mechanisms including poppet valves.

- 5 It is among the objects of the present invention to prevent lateral thrusts on the stem of the poppet valve during the operation thereof, thereby substantially reducing the wear on the valve stem and its bearing.
- 10 Another object is to prevent the excess lubricant on the valve operating mechanism from dripping upon the valve stem or engine head which will cause gumming and sticking of the valve and produce obnoxious odors of
- 15 burning oil respectively.

A still further object is to maintain the entire valve mechanism as cool as possible.

Further objects and advantages of the present invention will be apparent from the following description, reference being had to the accompanying drawings, wherein a preferred form of the present invention is clearly shown.

In the drawings:

- 25 Fig. 1 is a detail view showing the valve mechanism housing and one of the valve operating devices in section while the adjacent valve operating device is shown in elevation.
- 30 Fig. 2 is a side view of the Fig. 1, certain parts being shown in section.

Referring to the drawings, the numeral 20 designates the head of an engine cylinder provided with poppet valves including 35 stems 21 and 22, supported in bearing-guides 23 and 24. The valve is moved into engagement with its valve seat by means of a spring 25, interposed between two abutment collars 26 and 27. The collar 26 rests on a shelf 40 formed on the valve-stem guide 23, while the spring 25 holds the collar in engagement with the split washer 28, which is inserted in the circumferential groove 29 formed near the end of the valve stem.

- 45 A housing 30 is secured to the top of the cylinder structure by means of feet 31. These feet project beyond the lower surface of said housing, thereby providing a space 32 between said housing and the cylinder 50 structure. Air may flow through this space and aid in keeping the valve mechanism and this portion of the cylinder structure cool. The housing is adapted to support the rocker-arm shaft 33 which in turn is provided with 55 a pair of rocker arms each comprising a hub

portion 34 having two oppositely-disposed lever arms 35 and 36. The lever arm 35 is in driving connection with the engine cam shaft (not shown), by means of the push rod 37.

60 The housing 30 comprises also a pair of cylinders 38 each of which is provided with a cup-shaped plunger 39 slidably arranged therein in an inverted position. The upper inside surface or ceiling of the plunger 65 engages with the end of the valve stem both having a common axis.

65 The end of lever arm 36 of the rocker arm is adapted to engage with the outer surface of the plunger approximately at its center.

70 From the foregoing it will be seen that the plunger 39 which is adapted to slide in the cylinders 38, axially with the valve stem, is interposed between the valve stem and the rocker-arm lever which operates it. Thus 75 the circular oscillations of the rocker-arm lever 36 about the shaft 33 cannot exert a lateral thrust on the valve stem due to the sliding plunger 39 being interposed therebetween. Lateral thrust of the lever arm 36 80 is dissipated by the sliding movement of the arm relative to the top of the plunger 39.

An inverted funnel-shaped element or 85 apron 40 is provided in each of the cylinders 38, the larger portion of the element tightly fitting in the lower end of the cylinder while the reduced portion extends into the cup-shaped plunger. This forms a circular space 41 between said element and the inside wall of the cylinder. A drain hole 90 90 is provided in the cylinder wall forming communication between the outside of the cylinder and the space 41.

This space is adapted to catch any excess lubricating oil applied to lubricate the 95 plunger and cylinder contacting surfaces and prevent this excess of oil from dripping onto the valve stem and cause gumming and sticking thereof.

The drain hole 42 will permit the oil to 100 flow from the space 41.

The housing is provided with walls 43 forming a pan-like structure in which drippings of excess oil on the rocker arms can be accumulated from whence this oil may be conducted to the oil supply in any suitable manner. The drain holes 42 discharge their oil into this pan-like structure.

105 It may be clearly seen that any excess lubricant used in connection with the valve

mechanism of the engine will be prevented from reaching the engine thereby eliminating the obnoxious smell caused by permitting oil to drop on a hot engine.

5. While the form of embodiment of the invention as herein disclosed, constitutes a preferred form, it is to be understood that other forms might be adopted, all coming within the scope of the claims which follow.

10. What is claimed is as follows:

1. A valve mechanism for an internal-combustion engine comprising, in combination, a housing formed with a bore, a poppet valve having one end adapted to enter the said bore; a rocker arm for operating the poppet valve; means capable of movement only axially of the valve interposed between the valve and rocker arm whereby lateral thrust on the valve stem is eliminated and stationary means associated with the first named means adapted to co-operate with the wall of the said bore to form an outer annular chamber for receiving excessive lubricant from the said first named means.

2. A valve mechanism for an internal-combustion engine comprising, in combination, a poppet valve; a rocker arm for operating the poppet valve; a housing supported on the engine, adapted to support the rocker arm and including a cylindric orifice into which a part of the poppet valve extends; and a plunger in said cylindric orifice interposed between the valve and the rocker arm, said plunger being movable axially of the valve to substantially eliminate lateral thrust on the valve stem and a cylinder adapted to engage the wall of the said orifice and formed with an upper reduced portion for making with said wall an annular oil drip chamber.

3. A valve mechanism for an internal-combustion engine comprising, in combination, a housing having feet for supporting it on the engine and providing a space between the engine and housing proper and including a cylindrical portion; a rocker arm supported by the housing; a poppet valve including a stem which extends into the cylindrical portion of the housing; a cup-shaped plunger, slidably arranged in the cylindrical portion and interposed between the rocker arm and the valve stem; a funnel-shaped member provided in the cylindrical portion, the larger portion of said member fitting tightly in said portion while the smaller portion extends into the cup-shaped plunger, thereby forming a chamber between the funnel member and its containing cylinder; and draining means in the cylinder portion of the housing communicating with said chamber.

4. Valve operating mechanism for operating engine valves of the poppet type comprising, in combination, a frame adapted to

be attached to the engine cylinder block; valve operating mechanism including rocker arms supported by the frame; a single cap and a cylindrical apron included on the frame formed to extend into the cap for preventing excessive lubricant of the valve operating mechanism from coming in contact with the cylinder block.

5. Valve operating mechanism for operating engine valves of the poppet type comprising, in combination, a frame adapted to be attached to the engine cylinder block; valve operating mechanism including rocker arms supported by the frame; an actuating cap, and means extending into the said cap and included on the frame for preventing excessive lubricant of the valve operating mechanism from coming in contact with the cylinder block and the stems of the poppet valves.

6. The combination of a valve stem, a valve stem housing therefor including a cylindrical bore constructed to receive the said stem in spaced relation with respect to the walls of the said bore, a cap adapted to slide within the said bore and transmit solely in an axial direction the thrusts imparted thereto, means to engage and operate the cap, a cylindrical apron fixedly mounted at the lower end of the said bore and forming an oil tight connection therewith, the said apron serving in co-operation with the wall of the said bore to form an annular chamber for directing particles of dirt and excessive lubricant into and adjoining the drainage chamber.

7. The combination of a valve stem, a valve stem housing therefor, including a cylindrical bore constructed to receive the said stem in spaced relation with respect to the walls of the said bore, a cap adapted to slide within the said bore and transmit solely in an axial direction the thrusts imparted thereto, means to engage and operate the cap; a valve spring, an apron carried at the lower extremity of the said bore and extending upward in reduced proportions so as to loosely fit the said cap and provide a means of preventing grit and lubricant from gaining access with the said spring.

8. A valve mechanism for internal combustion engines comprising in combination, a frame adapted to be attached to the engine cylinder block, a rocker arm supported in the said frame, a poppet valve including a stem which extends into a cylindrical bore of the said housing, a cup shaped plunger slidably arranged in the upper end of the bore of the housing and actuated by the said rocker arm; means fixedly attached to the lower end of the said bore and having an upward reduced extension for providing, with the wall of the said bore, an annular chamber in which the said cup shaped plunger operates and forming a detention

chamber for oil drippings; and draining means in the said housing adjacent the wall of the said bore, for communication with the said chamber for disposition of the said 5 drippings.

9. A valve mechanism for internal combustion engines comprising, in combination, a frame adapted to be attached to the engine cylinder block, a rocker arm supported in 10 the said frame, a poppet valve including a stem which extends into a cylindrical bore of the said housing, a cup shaped plunger slidably arranged in the upper end of the bore of the housing and actuated by the said 15 rocker arm; means fixedly attached to the lower end of the said bore and having an up-

ward reduced extension for providing, with the wall of the said bore, an annular chamber in which the said cup shaped plunger operates; a tubular member carried at the 20 lower end of the said bore and providing an oil tight connection with the wall thereof and extending upwardly in reduced proportions into the said cup shaped plunger for constituting with the wall of the said bore a 25 lubricant receiving chamber; and means formed in the said housing adjacent the wall of the said bore communicating with the said chamber for draining the latter.

In testimony whereof I hereto affix my 30 signature.

GEORGE E. A. HALLETT.
